(57) **CLAIM**

The ornamental design for a cryoablation equipment, as shown and described.

DESCRIPTION

FIG. 1 is a perspective view of a cryoablation equipment showing the present design in an open configuration;

FIG. 2 is a front end view thereof;

FIG. 3 is a rear end view thereof;

FIG. 4 is a right side view thereof;

FIG. 5 is a left side view thereof;

FIG. 6 is a top plan view thereof; and

FIG. 7 is a bottom plan view thereof.

FIG. 8 is a perspective view of a cryoablation equipment showing the present design in a closed configuration;

FIG. 9 is a front end view thereof;

FIG. 10 is a rear end view thereof;

FIG. 11 is a right side view thereof;

FIG. 12 is a left side view thereof;

FIG. 13 is a top plan view thereof; and,

FIG. 14 is a bottom plan view thereof.

The broken lines shown in the figures are included for the purpose of illustrating portions of the cryoablation equipment and form no part of the claimed design.

1 Claim, 14 Drawing Sheets
